ABSTRACT: An air heater for outdoor work areas including an elongated linear burner containing fire tube having a heat discharging blower mounted in alignment with and in spaced relation from the outlet end of the tube. The portion of the tube adjacent the outlet end includes upper and lower combination air inlets and gas exhausts. The unit is skid mounted for portability.

AIR HEATER WITH SAFETY EXHAUST SYSTEM

The instant invention generally relates to heater assemblies of the type utilized in heating outdoor work areas such as drilling rigs, construction sites and the like. More particularly, the invention is concerned with such a heater assembly wherein specific provision is made so as to protect the blower and the work area itself against any possible harmful malfunctioning of the burner equipment.

Portable heaters of the type herein involved are normally utilized so as to maintain temperatures at outdoor worksites which allow for a continuation of the work under reasonably comfortable conditions regardless of prevailing cold weather conditions. In apparatus of this type, utilizing a gas-fed burner unit, problems occasionally arise in the equipment which could result in a highly undesirable discharge of gas into the work area. As one example of such a situation, there might be a fire failure in the burner in conjunction with a failure of the appropriate control valve to cut off the gas supply. In addition to this particular hazard, there is also the danger of damage to the equipment itself, and more particularly the blower should, as an example, the burner stay on because of a safety valve failure subsequent to a stopping of the blower. Accordingly, it is the primary intention of the instant invention to construct an area heater, utilizing an elongated fire tube from which burner-heated air is drawn and directed to a worksite by a blower, wherein substantial safety features are incorporated in a simple and highly unique manner, such being done so as to produce an extremely effective protection system in an economical and practical manner.

In conjunction with the above object, it is a significant object of the instant invention to provide a "safe" system which, during the normal operation thereof, provides for a complete combustion of the fuel and a dependable continuous high temperature discharge.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIG. 1 is a side elevational view of the air heater of the instant invention;

FIG. 2 is a top plan view thereof;

FIG. 3 is an enlarged longitudinal cross-sectional view taken substantially on a plane passing along line 3-3 in FIG. 2;

FIG. 4 is a transverse cross-sectional view taken substantially on a plane passing along line 4-4 in FIG. 3;

FIG. 5 is a side elevational view of the air heater with an insulating cover utilized over the fire tube and controls; and

FIG. 6 is a plan view of a modified form of support skid.

Referring now more specifically to the drawings, reference numeral 10 is used to generally designate the portable air heater comprising the instant invention. The heater 10 consists basically of an elongated hollow cylindrical fire or burner tube 12, a burner unit 14 mounted within one end of the tube 12, and a blower unit 16 positioned in spaced aligned relation to the other end of the tube 12.

The fire or burner tube 12 and blower unit 16 are normally mounted on an elongated skid 18 consisting of a pair of laterally spaced elongated side beams 20 interconnected by transversely extending rigid pipes 22. The tube 12 will be supported in an elevated position above the skid 18 by appropriate legs 24 while the blower unit 16 will be mounted on the skid 18 through an appropriate base construction 26 in a manner so as to position the blower intake or inlet 28 at equal height and in alignment with the spaced outlet or discharge end 30 of the tube 12. If so desired, an overhead support rack or frame 32 can be mounted on the skid 18 for the support of blower extension tubes or ducts 34 which can be added to the blower outlet or discharge 36, these duct sections 34 being secured by a tiedown line 37 selectively tightened by an appropriate line or chain tightener 38.

As noted previously, the burner unit 14, which can actually consist of multiple burners as suggested in FIG. 4, is mounted

within the fire or burner tube 12 adjacent one end thereof, this one end, designated by reference numeral 40, constituting the inlet end of the tube. The inlet end 40 of the tube is closed by an end wall 42 having a selectively openable enlarged access panel 44 therein whereby servicing of the burner unit 14 can be easily effected. The fuel supplying and control lines 46 for the burner unit 14 extend into the first end 40 of the fire tube 12 through an enlarged opening 48 through the lower portion of the tube 12 immediately forward of the end wall and closure panel 42 and 44, this opening also constituting the primary air intake for the burner unit 14. Appropriate control valves, pressure gauges and the like, generally designated by reference numeral 50, will be located outward of the fire tube 12 and constitute the control means for the burner unit and gas supply lines.

Immediately inward of the outlet or discharge end 30 of the fire tube 12, the tube 12 is provided with an enlarged screen protected air intake 52 extending at least 180° about the tube 12 transversely about the lower portion of the tube 12. As will be appreciated from the drawings, this screened air intake opening 52, which incidently also functions as a gas exhaust as shall be explained presently, extends along a substantial length of the fire tube 12 commencing immediately inward from the discharge end 30.

A second air intake at the outlet or discharge end portion of the tube 12 is provided in the nature of a vertical screened flue 54 projecting upwardly from the fire tube in general alignment with the inner portion of the downwardly directed opening 52, this flue 54 selectively acting in the manner of an air inlet or a gas exhaust stack. Finally, as noted previously, the blower unit 16 is spaced from the discharge end 30 of the fire or burner tube 12 so as to provide a substantial and a complete airgap or space therebetween.

Constructed in this manner, the heater 10 inherently incorporates significant safety features which substantially enhance the adaptability of the heater for all working environments. More particularly, not only do the opening 52 and flue 54 provide secondary air intakes forward of the burner unit 14 so as to ensure a complete combustion of the fuel prior to a discharge of the heated air by the blower unit 16, but also, these openings function as exhausts should any malfunction of the apparatus occur. For example, should there be a fire failure within the burner unit 14 without a corresponding cutting off of the gas, the heavy gas will merely move downwardly through the opening 52 and discharge in the area of the heater rather than passing through the blower and air ducts leading to the work area. The significant airgap between the inlet 28 of the blower 16 and the discharge end 30 of the fire tube 12 also contributing to the gas discharging to the atmosphere prior to being directed to the work area.

As another example, should the blower 16 cut off without a corresponding cutting off of the burner unit and gas flow, the hot air, including the exhausted gas, will freely pass upwardly and exhaust or exit through the upwardly directed flue 54 rather than passing into the blower unit 16 and causing possible damage thereto. In this particular situation, while the heat within the fire tube 12 can increase substantially, the fire tube is specifically constructed so as to withstand the heat, and at the same time, the significant airgap between the blower unit 16 and the fire tube 12 prevents a transmission of this heat to the blower unit wherein, in the absence of an activation of the blower unit 16, substantial damage might be done. Incidentally, the air space between the blower unit 16 and the fire tube outlet end 30 also functions as an extra exhaust area for the gas and heat in the event of blower failure, as well as a means for allowing the addition of an appreciable amount of fresh air during the operation of the heater which air, being taken from closely adjacent the fire tube 12 itself, will in fact be slightly preheated.

Also of significance in spacing the blower unit 16 from the fire tube 12 as compared to an engaged side-by-side positioning of these units, is the elimination of any possibility of the fire tube being forced against and possibly causing

damage to the blower unit as the heater is being moved. In this regard, it will of course be appreciated that the use of the heater at remote outdoor worksites will require a subjecting of the heater to relatively rough handling, this in turn requiring a rugged trouble-free construction.

Referring specifically to FIG. 5, it should be recognized that the heater assembly of the instant invention can provide for an enclosing of the fire tube 12 within an insulated protective housing 56, this housing 56 also enclosing the control apparatus 50. As will be appreciated from FIG. 5, the fire tube discharge end 30 as well as the flue 54 will open directly through the housing walls 56 with the end of the housing being generally coextensive with the discharge end 30 of the fire tube 12 so as to retain the complete airspace or gap between the blower unit 16 and fire tube 12. In addition, if deemed desirable so as to accommodate the air intake or gas exhausting action of the fire tube opening 52, the adjacent end wall of the housing 56 can be entirely open below the fire tube discharge end 30, or alternatively suitable grilles openings can be provided through the lateral sidewalls of the housing 56 adjacent this end of the fire tube 12.

Referring now to FIG. 6, an enlarged skid 58 has been illustrated therein, this skid 58 incorporating an additional laterally joined section 60 for transporting additional air duct section 62 either in conjunction with or in place of the overhead rack 32 provided on the skid 18.

From the foregoing, it will be appreciated that a unique heater assembly has been defined. This heater assembly includes a fire tube comprising a single straight length of constant diameter hollow tubing, so as to achieve maximum heat flow from the burner unit, and a safety exhaust system which protects both the blower unit and the actual work area should any malfunction of the equipment occur. This exhaust means includes, in addition to an enlarged downwardly directed screened or grill-covered opening for heavy gas and an upwardly directed screened or grill-covered flue for lighter burned or exhaust gas, a specific complete airgap between the open discharge end of the fire tube and the blower unit itself.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention.

I claim:

1. A heater assembly comprising an elongated fire tube, said fire tube including first and second ends, burner means mounted within said fire tube adjacent the first end, the second end of said fire tube being open and constituting the discharge end, blower means longitudinally aligned with and spaced from said discharge end for the drawing of burner heated air therefrom and the discharge of the air to an outwardly located area, and combination combustion supporting air inlet and gas exhaust means within said fire tube adjacent the discharge end thereof, said combination means being orientated relative to the burner means whereby air

introduced therethrough will insure a substantially complete combustion of the fuel prior to discharge of the heated air, said combination air inlet and gas exhaust means including an upwardly directed flue through the top of said fire tube and a downwardly directed opening transversely across the lower portion of said fire tube.

2. The heater assembly of claim 1 wherein said fire tube includes a primary air inlet therethrough adjacent said burner means, said fire tube being of a constant cross section along 10 the full length thereof.

3. The heater assembly of claim 1 wherein the downwardly directed opening transversely across the fire tube extends about the tube for at least approximately 180°.

4. A portable area heating heater assembly comprising an 15 elongated fire tube including first and second ends, burner means mounted within said fire tube adjacent the first end thereof, primary air inlet means in said tube adjacent said burner means, the second end of said fire tube constituting the discharge end, blower means positioned adjacent the 20 discharge end of said fire tube for the drawing of heated air therefrom, and first and second combination secondary combustion air inlets and gas exhaust openings through said fire tube immediately adjacent the discharge end thereof and in direct communication with the atmosphere, the first and 25 second combination openings comprising an upwardly directed opening through the top of said fire tube and a downwardly directed opening through the bottom of said fire tube in general alignment with each other, said openings being orientated relative to the burner means whereby air introduced therethrough will insure a substantially complete combustion of the fuel prior to discharge of the heated air, the upwardly directed opening comprising a screened flue, and the downwardly directed opening being elongated 30 transversely across the lower portion of the fire tube and screen protected.

5. A portable area heating heater assembly comprising an 35 elongated fire tube including first and second ends, burner means mounted within said fire tube adjacent the first end thereof, primary air inlet means in said tube adjacent said burner means, the second end of said fire tube constituting the 40 discharge end, blower means positioned adjacent the discharge end of said fire tube for the drawing of heated air therefrom, and first and second combination secondary combustion air inlets and gas exhaust openings through said 45 fire tube immediately adjacent the discharge end thereof and in direct communication with the atmosphere, the first and second combination openings comprising an upwardly directed opening through the top of said fire tube and a downwardly directed opening through the bottom of said fire 50 tube in general alignment with each other, said openings being orientated relative to the burner means whereby air introduced therethrough will insure a substantially complete combustion of the fuel prior to discharge of the heated air, said blower being longitudinally spaced from the discharge 55 end of the fire tube so as to define a complete airgap therebetween.
